UNITED STATES PATENT OFFICE.

JOHN S. HULL, OF BALTIMORE, MARYLAND.

CUT-OFF MECHANISM FOR VAPOR HEATING APPARATUS.

SPECIFICATION forming part of Letters Patent No. 269,576, dated December 26, 1882.

Application filed October 18, 1882. (No model.)

To all whom it may concern:

Be it known that I, JOHN S. HULL, a citizen of the United States, residing at Baltimore, Maryland, have invented certain new and useful

5 Improvements in Cut-off Mechanism for Vapor Heating Apparatus, of which the following is a specification, reference being had to the accompanying drawings, forming part hereof, in which—

10 Figure 1 is view partly in section and partly in elevation, showing my invention. Figs. 2, 3, and 4 are detail views.

Like letters mark the same parts in all the figures.

15 A A are tanners' fire-pots, mounted on a table or bench, A'. a are branch pipes leading to the burners A², for heating said fire-pots. The particular construction of these pots and burners may be varied as may be desired.

20 B is a main supply-pipe, leading from a tank, C, containing the fluid-supply. This supply-pipe furnishes oil to the burners under pressure, and is set at angle inclining slightly downward from the burner to the tank, for a purpose to be described.

25 D is an air-pump, which forces air through a pipe, d, to an air-tank, E, from which the air passes through a pipe, F, to the supply-tank C. The compressed air passing into this tank causes the oil to pass from the tank to the burners.

30 G is a pipe leading from the waste-tank H. h is a branch pipe leading from the pipe F to the tank H, and K is a pipe leading from the main supply-pipe to the tank H. The pipe B is provided with a cut-off valve, b, and a three-way valve, b', the pipe d with a valve, d', the pipe F with two valves, f f', the pipe G with a valve, g, and the pipe h with a valve, h', the uses of which will be hereinafter described.

35 I is a vent-valve mounted upon the tank H, and is shown in detail in Fig. 2.

The three-way valve b' is illustrated in two positions in Figs. 3 and 4. b² is a lever pivoted to the stem of said valve, and carries a weight, b³. This weight is held up in the position shown in Fig. 1 by a string, b⁴, passing over pulleys b⁵, overhead or in front of the workman using the fire-pots. When it is desired to supply the fire-pots with fluid the pump is operated, compressing the air in the tank E. The valves b f f'

being open, the compression of the air in the tank forces it through the pipe F into the supply-tank C, forcing the fluid therefrom through the pipe B to the burners, which heat the fire-pots. When, by reason of any accident, it is desired to suddenly shut off the supply the string b⁴ is cut, allowing the weight b³ and lever b² to drop, turning the three-way valve to the position shown in Fig. 4. This cuts off the supply from the tank C through pipe B, and causes the flame at the burners to be extinguished, and at the same time opens a way through the three-way valve for whatever oil there may be in the pipes to pass down through pipe K to the tank H, leaving pipes clear. When it is desired to employ the waste-tank the valve f' is closed and the valves g and h' opened. The compressed air in the tank E will now pass from thence to the tank H through the pipes F, and force the fluid contained in the tank H into the supply-tank C, from whence it will be again forced into the burners. The vent-valve I must also be closed while forcing the fluid out of the tank H.

The string b⁴ may be an ordinary twine or any kind of small wire suitable for the purpose.

My cut-off apparatus is here shown in connection with tanners' fire-pots; but I desire to say that its use is not restricted to this application. The means I employ, as here described, may be used in connection with any devices wherein vapor-burners are employed.

Having thus fully described my invention, what I claim, and desire to secure by Letters Patent of the United States, is—

1. The combination, substantially as described, of a series of burners, a branch supply-pipe for each, a main supply-pipe set at an inclination and having branches leading to a supply-tank, a valve, b', and means for operating it, and a tank for receiving the waste oil, as set forth.

2. The combination, substantially as described, of a series of burners, a branch pipe for each, a main supply-pipe set at an inclination, a three-way valve therein, and a pipe leading therefrom to a waste-tank, whereby the supply of oil may be cut and the wasteway opened by one and the same operation, as set forth.

3. The combination of the main supply-pipe,

set at an inclination, the pipe to the waste-tank, the three-way valve at their junction, a weighted lever attached to said valve, and means for dropping said lever to cut off the supply and open the wasteway, as set forth.

5. The combination, substantially as described, of the series of burners, a branch pipe for each, an inclined supply-pipe, the waste-tank, the three-way valve, its weighted lever, 10 and the string attached thereto and suspended above the heads of the workmen.

4. The combination, substantially as described, of the series of burners, a branch pipe for each, an inclined supply-pipe, the waste-tank, the three-way valve, its weighted lever, 15 and the string attached thereto and suspended above the heads of the workmen.

5. The combination of an air-pump, an air-tank, a pipe, F, leading from the air-tank to the supply-tank, a branch, h, therefrom to the waste-tank, and a pipe, G, connecting the waste-tank with the supply-tank, the pipes being arranged as shown and supplied with suit-

able valves, whereby the air is forced directly into the supply-tank or through the waste-tank, forcing the waste oil into the supply-tank, as set forth.

6. The combination of a series of burners, a fluid supply-tank, a main supply-pipe connecting them, a waste-tank, a pipe leading from it to the supply-pipe, a three-way valve 25 at the junction of the two pipes, and means for simultaneously cutting off the supply and opening the wasteway, as set forth.

In testimony whereof I subscribe my name.

JOHN S. HULL.

In presence of—

S. BRASHEARS,
JNO. T. MADDOX.
